John P. Kelly
ATTORNEY

UNITED STATES PATENT OFFICE.

FRANCESCO MARINO, OF BROOKLYN, NEW YORK, ASSIGNOR TO LAURA M. DE SUAREZ, OF BROOKLYN, NEW YORK.

STORM HOSE.

Application filed August 19, 1926. Serial No. 130,151.

This invention relates generally to storm hose to be worn over the shoe and stocking, under the skirt or trousers, the invention having more particular reference to 5 a novel type of storm hose.

The invention has for an object the provision of an improved storm hose, comfortable to the wearer, and embodying adjustable fitting qualities.

10 A further object of the invention is the provision of an improved storm hose of simple construction and novel arrangement of parts.

For further comprehension of the invention, and of the objects and advantages thereof, reference will be had to the following description and accompanying drawings, and to the appended claims in which the various novel features of the invention 20 are more particularly set forth.

Fig. 1 of the drawings, is a side elevational view of my improved storm hose, showing same applied to the wearer, as it would appear when in use.

25 Fig. 2 is an enlarged fragmentary vertical sectional view of the knee portion thereof.

Fig. 3 is a transverse elevational view taken on the line 3—3 of Fig. 2.

Fig. 4 is a similar sectional view taken 30 on the line 4—4 of Fig. 2.

As here embodied my improved storm hose comprises a hose member proper, of water-proof material, rubber, rubberized fabric, or the like, having a foot element 10, 35 shaped or formed to enclose or cover the shoe of the wearer, and having a leg element 11, shaped or formed to enclose or cover the leg of the wearer, and of suitable length to extend over the calf and knee of 40 the wearer and terminating, as at 13, above the said knee.

I have provided a longitudinal opening 14, located in the leg element 11, extending from above the foot element 10, upwardly, 45 slightly below the knee, so as to facilitate the applying of my improved storm hose to the wearer. The opening 14 is provided with inter-locking members 15, attached thereto, along the edges of the opening 14, 50 and projecting inwardly therefrom, toward each other, and adapted to close the said opening 14, when the slideable locking member 16, is pulled upwardly, as shown in Fig. 1 of the accompanying drawing. Devices 55 of this nature are in common use, for the

above mentioned purpose in connection with wearing apparel, tobacco pouches, bags, and the like. The above described construction being such as will secure a good fitting storm hose, affording comfort to the wearer. 60

The self-fitting member 19, preferably of comparatively thin spring steel, or the like, is formed broad at 20, and narrower at 21, so as to snugly fit the knee of the wearer, and is formed or bent circularly, and is 65 provided with an elongated slot 22, located in proximity to one extremity thereof. The pin 23, is attached to the self-fitting member 19, at or near the other extremity thereof, and is adapted to engage in the elongated slot 22, and is provided with an enlarged head 24, so as to secure the engagement of the said pin. The above described construction being such as will permit the tension of the self-fitting member 19 to conform to the knee of the wearer, and to slidably expand, so as to adjust itself to different wearers, as is necessary to secure a close fitting, and comfortable storm hose, and which will prevent my improved device 70 75 80 from interfering with the skirts or trousers or outer garments of the wearer.

The self-fitting member 19 is positioned over the hose member proper, at the knee thereof, as clearly shown in Fig. 2, and has 85 attached thereto, at its inner and outer surfaces, protecting strips 25 and 26, respectively, of any soft, pliable material, such as cotton flannel, or the like.

The outer member 27, of rubber, rubberized fabric, or the like, is adapted to cover the knee portion of the hose member proper, and is extended between the above mentioned elastic members 17 and 18, and is 90 sewn, stitched, or otherwise attached there- 95 to at its upper and lower edges, as at 28 and 28' so as to form a pocket, which will permit the said self-fitting member 19, to be slid therein, so as to secure the proper location or position of the self-fitting member, 100 so as to accommodate persons having different leg lengths.

The elastic members 17 and 18, preferably rubber fabric, or the like, are sewn, stitched, or otherwise attached to the hose member 105 proper, directly above and below the extremities, respectively of the outer member 27, and extend longitudinally around the outer surface of the hose member proper. A similar elastic member 18', is positioned 110

over the outer member 27, and is positioned over the knee, by sliding the said elastic member 18' to the desired position, as is necessary to accommodate wearers having different leg lengths. The above described construction being such as will insure a good fitting storm hose, which will not interfere with the outer garments of the wearer.

While I have above described the preferred form, construction and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

Having thus described my invention, what I claim as new and desire to protect by Letters Patent of the United States is as follows:

1. In a storm hose of the class described, an elastic member and a second elastic member attached thereto, directly below the knee and at the upper edge thereof respectively, and extending longitudinally around the outer surface thereof, a third elastic member slidably positioned over the outer member, so as to insure a good fitting device.
2. In a storm hose of the class described, a leg element, an outer member adapted to cover the knee portion thereof, an elastic member and a second elastic member attached at the upper and lower edges of the said outer member, the said elastic member and second elastic member being also attached to the storm hose, and a third elastic

member slidably positioned over the said outer member.

3. In a storm hose of the class described, a leg element, an outer member adapted to cover the knee portion thereof, an elastic member and a second elastic member attached at the upper and lower edges of the said outer member, the said elastic member and second elastic member being also attached to the storm hose, so as to form a pocket, a self-fitting member adapted to fit the knee of a wearer, said self-fitting member being positioned in the said pocket so as to permit the self-fitting member to slide therein to accommodate the said wearer's knee.

4. In a storm hose of the class described, a leg element, an outer member adapted to cover the knee portion thereof, an elastic member and a second elastic member attached at the upper and lower edges of the said outer member, the said elastic member and second elastic member being also attached to the storm hose, so as to form a pocket, a self-fitting member adapted to fit the knee of a wearer, protecting strips attached to the inner and outer surfaces of the self-fitting member, said self-fitting member being positioned in the said pocket so as to permit the self-fitting member to slide therein to accommodate the said wearer's knee.

In testimony whereof I have affixed my signature.

MARINO, ^{his} X FRANCESCO.
